HEAD FOR A SELF-WRINKING MOP

Jean Charles Delacretaz, 26 Roosevelt St.,
North Coburg, Victoria, Australia

Filed Aug. 13, 1962, Ser. No. 71,262

Claims priority, application Australia Apr. 9, 1962

Term of patent 14 years

(Cl. D9—2)

FIGURE 1 is an elevational view taken from one end of the head for a self-wringing mop embodying my new design, the opposite end being a mirror image of the end shown;

FIGURE 2 is a front elevational view thereof;

FIGURE 3 is a rear elevational view thereof;

FIGURE 4 is a top plan view thereof; and

FIGURE 5 is a bottom plan view thereof.

I claim:

The ornamental design for a head for a self-wringing mop, as shown and described.
